2 SHEETS—SHEET 2.

UNITED STATES PATENT OFFICE.

WILLIAM SCHOTT, OF FLINT, MICHIGAN.

DEVICE FOR LIFTING THE FRAMES OF RAILROAD-TRUCKS.

SPECIFICATION forming part of Letters Patent No. 757,507, dated April 19, 1904.

Application filed October 27, 1903. Serial No. 178,706. (No model.)

To all whom it may concern:

Be it known that I, WILLIAM SCHOTT, a citizen of the United States, residing at Flint, in the county of Genesee and State of Michigan, 5 have invented new and useful Improvements in Devices for Lifting the Frames of Railroad-Trucks, of which the following is a specification.

This invention relates to improvements in 10 an apparatus for lifting the frames of railroad-trucks without removing the wheels from the tracks.

Heretofore when the brasses of bearings became hot or worn and had to be removed 15 while the train was on the road it required considerable time and labor to make the necessary repairs.

It is therefore the purpose of my invention to overcome the objectional delays and cumbersome operations incident thereto and provide an apparatus which can be quickly and conveniently handled, that the brass may be removed with comparatively little delay.

A further object of the invention is to provide 25 an apparatus for elevating the truck-frame without lifting the wheels from the tracks, which is operated by the movement of the engine or car, as the case may be, and therefore dispense with the use of manually-operated mechanism for this purpose.

In the drawings, Figure 1 is a vertical central section of a truck and my invention applied and ready to be operated. Fig. 2 is a detail view of the same, but showing the truck-frame elevated. Fig. 3 is a transverse section on the line 3-3, Fig. 2. Fig. 4 is a similar view, but illustrating the position of the lifter before the truck is moved and disclosing a slight modification. Fig. 5 is a perspective view of the preferred form of my invention. Fig. 6 is a vertical section of the same. Fig. 7 is a transverse section on the line 7-7 of Fig. 6. Fig. 8 is a detail perspective view of the modification of the lifting-block shown in Fig. 4 and illustrating a filler-block which coacts therewith.

The same numerals refer to like parts in all the figures.

1 represents a railroad-track, and 2 the ties 50 supporting the same. A truck 3 is mounted

on the tracks, and as it is essential to a comprehensive understanding of my invention that the movements of the truck be understood a general statement of the parts will be given. The wheels 4 are carried on an 55 axle 5, mounted in bearings 6, comprising the usual collar 7, brass 8, and box 9. The box is mounted to slide on the frame 10, composed of the upper stringer 11 and the tie-rod 12. Parallel bars 13 connect the adjacent boxes 10, 60 and a spring 14 is placed between the stringer 11 and hangers between said bars 13.

I have described only one side of the truck; but as the structure is so well known it is to be understood that both sides are identical. 65

16 represents a base-block which is inclined on its upper surface 17 and is provided with ways 18. Depending from the under side of the block are pins or the like 19, which are embedded in the ties 2 when the invention 70 is being operated. A lifting-block 20 is provided on its lower side with an inclined surface 21 and adjacent ribs forming ways 22, which work in the ways 18 of block 16, the upper surface of said lifting-block being flat 75 ribs 22 the under side of the lifting-block is and on a horizontal plane. Intermediate the provided with a series of grooves 23, into which fit and freely roll on the surface 17 antifriction-rollers 24. The lifting-block is 80 limited in its movement up the inclined surface 17 by a stop 25, and its movement in the opposite direction is checked by a pin or bar 36.

In Figs. 4 and 8 I have shown two slight modifications to adapt the invention to certain kinds of trucks and conditions likely to come about. The lifting-block is centrally grooved at 20° to form two upstanding flanges 27 27, which straddle the tie-rod 12 and bear directly on the bottom of the box 9. Should 85 the bottom of the truck-frame be a little high from the ties and it is desired to lift the frame and not the box, a filler-piece 29 may be dropped in the groove 20° of the lifting-block. Piece 29 has end flanges 30 30, which 90 lock it to the lifting-block when it is dropped in place.

In operation the apparatus is seated on the cross-ties 2, the lifting-block being at the lowest level, with its upper flat surface under 100

the tie-rod 12 at a point below the journal to be elevated for the removal of its brass, as shown in Fig. 1. The box-fastening devices 31 are removed and the collar 7 is withdrawn, and in order that the space between the bottom of the box 9 and the flange 32 of the collar may be filled up, that the lifting action may be applied directly to the box, I insert a filler 33, as shown in Fig. 2. The apparatus 10 having been positioned as shown in Fig. 1, the truck is moved in the direction of the arrow *a*. The nuts of the frame bearing against the edge of the lifting-block start it up the inclined surface of the base-block, and as soon 15 as it has moved far enough to take the weight of the truck it moves with the same. As the truck and the lifting-block are moved toward the highest part of the base-block the side frame of the truck and the box carried thereby are lifted from the axle, allowing the brass 8 to drop, that it may be withdrawn, as shown 20 in Fig. 2. The brass having been removed and another inserted in its place, the movement of the truck is reversed, which causes 25 the lifting-block to slide down the inclined surface. Hence the frame will assume its normal position on the axle. The apparatus is also removed, the filler 33 taken out, and the collar inserted and locked in the box, and the 30 operation of changing the brass is complete.

The operation is extremely simple and does away with the usual manual appliances for lifting trucks and positively insures the truck-frame being lifted from the axle and leaving 35 the wheels on the tracks.

The compactness and durability of the invention, combined with its simplicity, enables me to produce a lifting apparatus for the purpose specified of the highest commercial type. 40 My invention also contemplates a structure for operating directly on a journal-box to elevate it against the tension of the spring 14 and away from the axle. This modification is shown in Figs. 4 and 8. The groove 20^a 45 is so proportioned that it permits the lifting-block to move without engaging the tie-rod 12. However, the flanges 20 straddle said bar and bear directly against the bottom of the box. (See Fig. 4.) Such a construction 50 obviates the necessity of lifting the weight of the truck-frame notwithstanding the latter has been found preferable. The modified construction may also be utilized in connection with a filler-block (see Fig. 8) for use 55 when a truck-frame is slightly higher from the tracks than one of ordinary construction. For instance, if a tie-rod 12 of a standard truck is a predetermined distance from the ties and a truck of slightly-different proportions 60 had to be operated upon and the distance between its tie-rod and the ties was an inch or two greater than the standard the filler-block would be dropped into the groove 20^a 65 to form an inclined surface on a level with the top of the flanges. This arrangement fills

up the space between the bottom of a truck of unusual proportions and a standard lifting apparatus and enables me to lift it.

Having thus described my invention, what I claim is—

1. An apparatus for lifting a truck from its axle, comprising a base-block having an inclined surface with ways adjacent thereto, and a lifting-block having an inclined surface corresponding to the surface of the base-block, 75 ways adjacent to said inclined surface which coact with the ways of the base-block, said lifting-block being forced up the incline of the base-block for separating the truck from the axle thereof when said truck is moved, 80 substantially as described.

2. An apparatus for lifting a truck from its axle, comprising a base-block having an inclined surface with ways, a lifting-block having an inclined surface and ways, the inclination of the two blocks being the same and their ways coacting with each other, rollers intermediate the two blocks and bearing on the two inclined surfaces, the lifting-block being rolled up the inclined surface of the 90 base-block for separating the truck from the axle thereof when said truck is moved, substantially as described.

3. An apparatus for lifting a truck from its axle, comprising a base-block having an inclined surface, ways formed adjacent the inclined surface, a lifting-block having an inclined surface corresponding to the inclination of the base-block, ways on said lifting-block which coöperate with the ways of the base-block, the upper surface of the said lifting-block being flat, rollers between the two blocks, and means for limiting the movement of the lifting-block on the base-block, the lifting-block being rolled up the incline of the base-block for separating the block from the axle thereof by the movement of the truck, substantially as described.

4. An apparatus for lifting a truck from its axle, comprising a base-block having an inclined surface, a lifting-block having an inclined surface corresponding to the inclination of the inclined base-block, the upper surface of the lifting-block being flat and on approximately a horizontal plane for vertically lifting a journal from the axle supported thereby, the lifting-block being shorter than the base-block and guided thereon, and means for holding the blocks together, but allowing one to be moved lengthwise of its companion block, 110 but independent thereof, the lifting-block being moved up the incline of the base-block by the movement of the truck, substantially as described.

5. An apparatus for lifting a truck from its axle, comprising a base-block having an inclined surface, a lifting-block adapted to be slid up the incline surface of the base-block, said lifting-block being shorter than the base-block and guided thereon, the upper face of 120

the lifting-block adapted to lift a journal from the axle supported thereby, and means for holding the blocks together but allowing one to be moved lengthwise of its companion 5 block, but independent thereof, the lifting-block being moved up the incline of the base-block by the movement of the truck, substantially as described.

6. An apparatus of the class described, comprising a base-block having an inclined surface, a lifting-block adapted to slide up the inclined surface of the base-block, and a detachable filler-block, the filler-block fitting under a box of a truck, and the lifting-block 10 below the frame of the truck below the lifting-block, the lifting-block being moved up the incline of the base-block to elevate the truck and the filler-block by the movement of the truck, substantially as described.
- 15 7. An apparatus of the class described, comprising a base-block, and a lifting-block, the two blocks having surfaces, flanges on the upper surface of the lifting-block, a filler-block

adapted to be fitted between the flanges of the lifting-block, the lifting-block being moved 25 up the base-block by the movement of the frame carrying axles and wheels, to separate the axles from the frame, substantially as described.

8. An apparatus for lifting a truck from an axle comprising a lifting-block and a base-block, the lifting-block being shorter than the base-block and the faces of the two blocks being inclined in parallel relationship to each other, means for fastening the two blocks together, but allowing the lifting-block to be moved lengthwise the base-block by a truck 30 to separate its wheels from its frame, substantially as described.

In testimony whereof I have signed my name 40 to this specification in the presence of two subscribing witnesses.

WILLIAM SCHOTT.
